REINFORCING DEVICE FOR SILOS.

1,109,045.

Specification of Letters Patent.

Patented Sept. 1, 1914.

Application filed December 18, 1912. Serial No. 737,581.

To all whom it may concern:

Be it known that I, FRED P. CORY, a citizen of the United States, residing at Saginaw, in the county of Saginaw and State of Michigan, have invented certain new and useful Improvements in Reinforcing Devices for Silos; and I do hereby declare the following to be a full, clear, and exact description of the invention, such as will enable others skilled in the art to which it appertains to make and use the same.

This invention relates to silos and pertains more particularly to means for reinforcing silos constructed of staves and bound together by external hoops or bands.

The objects of the improvement are to provide means for preventing the collapse of a stave silo when empty and subjected to sidewise pressure of severe wind storms and hurricanes.

I have found in practice that the most frequent cause of collapse of silos when empty and subjected to such heavy wind pressure as above referred to, is due not only to the actual caving in of the side of the silo on account of the pressure against it, but is also due to a slight slipping lengthwise of some of the staves with respect to the adjacent staves, thus allowing the entire structure to take a tilted or leaning position, changing the horizontal cross-section of the silo from that of a circular to a somewhat elliptical shape. This weakens the structure and one of the sides is liable to give way by collapsing inward.

My invention provides reinforcing means independent of the hoops of the silo, which normally perform only the function of binding the staves together to form a cylindrical shell. This reinforcing means consists in a horizontal stiffening rib applied to the outside of the silo and fastened to the staves in such manner as to reduce their tendency to slide past each other and allow the silo to lean, while the circumferential expansion and contraction of the silo in no wise is interfered with. The stiffening rib also reinforces the staves against collapsing inwardly when subjected to extraordinary wind pressure.

With these and certain other objects in view which will appear later in the specification, my invention consists in the devices described and claimed and the equivalents thereof.

In the accompanying drawings, Figure 1

is a front view of a silo with my improvement applied thereto; Fig. 2 is a detail in perspective showing parts of three staves with a stiffening rib in place; Fig. 3 is a top view partly in section, showing a number of assembled staves with the stiffening rib in place; and Fig. 4 is a side view showing a preferred form of bracket by which the stiffening rib is applied to the staves.

As is clearly shown in the drawings, the device is applied to a silo composed of the usual staves 1 bound together by metal hoops 2.

In applying my invention I provide one or more circumferential stiffening ribs 3 which are secured to the outer faces of the silo staves by means of suitable brackets 4. These brackets are preferably secured to the staves by means of lag screws, wood screws, or other suitable device 5, there being preferably two of such screws for each bracket, one above and one below the stiffening rib.

The bracket is provided with a recess 6 shaped to slidingly receive the stiffening rib.

The stiffening rib preferably comprises a horizontal flange 7, projecting a considerable distance beyond the outer face of the staves in order to impart the required rigidity to prevent the staves collapsing inward when subjected to heavy sidewise wind pressure.

The stiffening ribs are also preferably provided with one or more vertical flanges 8 to give ample bearing surface against the faces of the staves.

The stiffening rib may be of any desired and suitable cross-sectional shape, as for instance, that of an angle, channel, T, or any other of the usual or well known forms in which structural steel is commonly made. In practice I prefer to apply a bracket 4 to every other stave of the silo in order that the brackets may be so close together as to counteract as much as possible any tendency of the adjacent staves to slip lengthwise upon each other and thus permit the silo to lean.

In practice I prefer that the fastening screws 5 shall not pass clear through the silo stave in order that the inner surfaces of the staves may be left smooth and unobstructed, but when desired through bolts may be used without departing from my invention.

While the stiffening rib 3 may be made

continuous like a hoop around the silo, it is not necessary and I prefer in practice to make it in several sections rather than in one continuous piece, both for convenience, cheapness in manufacture, and for ease in shipment and erecting. The ends of adjacent sections may be overlapped, as indicated at 9 in Fig. 3.

It will be understood that the stiffening rib does not act in the capacity of a binding hoop, but has for its function to impart stiffness to the exterior of the shell and act as a curved girder to prevent the inward collapse of the stave.

15 The stiffening rib, together with the brackets 4, also increases the resistance to movement of the staves past each other and thus helps to maintain the silo in an upright position.

20 By the means above described I have produced a stiffening device that acts independent of the hoops to counteract certain tendencies to collapse, which the hoops themselves are not capable of counteracting.

25 Having described my invention, what I claim and desire to secure by Letters Patent, is:—

1. In a reinforcing device for silos, the combination with the silo staves and the

external silo hoops; of a rib formed of sections, which sections have overlapping ends and a plurality of rib-engaging brackets secured to said silo at intervals to slidably receive said rib-sections and retain them from outward movement.

2. In a reinforcing device for silos, the combination with the silo staves and the external silo hoops; of a substantially L-shaped stiffening rib formed of sections, which sections have overlapping ends and means for slidably receiving said sections, for the purpose set forth.

3. In a reinforcing device for silos, comprising a flanged stiffening rib formed of sections, which sections have overlapping ends, spaced brackets secured to said silo and engaging the flange of said stiffening rib to hold same against vertical and outward movement, said stiffening rib being slidably engaged by said brackets, for the purpose set forth.

In testimony whereof, I affix my signature in presence of two witnesses.

FRED P. CORY.
